SELF-FEEDING SOLID COSMETIC CONTAINER

Albert Gelardin, New York, N. Y.

Application May 17, 1952, Serial No. 288,480

4 Claims. (Cl. 206—56)

The present invention relates to a self-feeding cosmetic container, and it particularly relates to a self-feeding cosmetic container to be used for holding perfumes.

It is among the objects of the present invention to provide an inexpensive, readily manufactured, self-feeding, solid perfume container.

Another object is to provide a novel self-feeding, solid perfume container which may be readily molded out of resin or other plastic and which will be made of few parts and which will be reliable in operation, without sticking, jamming and with assurance that the user or consumer will be able to readily operate the same and find the solid perfume always readily dispensable for consumption.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

In accomplishing the above objects, it has been found most suitable according to one embodiment of the present invention to prepare the casing of an external tubular member which may be molded of a plastic, such as a urea formaldehyde resin, which will have threaded connections to a removable top cap and a removable filler base.

Within this shell or container is desirably provided a thin sleeve or liner, as for example of a vinyl or other resin or even of metal, which may be held in position by the screw connection between the body sleeve and the screw base, and which at the same time will be provided at its upper end with an extension or a loop or bracket permitting access to the stick cosmetic while at the same time preventing ejection of the stick cosmetic.

Although the cosmetic may be provided with a screw feed, it is most desirably provided with spring-pressed plunger for pressing the stick cosmetic upwardly as it is consumed. The spring and plunger are desirably of such a construction as to maintain the stick cosmetic pressed against the extension strap or loop at the top of the liner without exerting sufficient pressure to cause deformation or rupture of the plastic material.

Where the sleeve or liner is of a flexible or plastic material such as a vinyl resin, such sleeve or container may be used as a gasket to protect the outer container from being affected by the contents of the cosmetic material.

In such case the outer container may be made of metal or plastic and protected from attack by the cosmetic material by the intervening sleeve or elastomeric material which is resistant to and inert in respect to the contents.

Although it is desired to mold the inner and outer casings or sleeves of a transparent plastic, it is also possible to use colored effects on the inside sleeve or even advertising or printed material which may be read or will be visible through the outer sleeve.

Although the inner and outer sleeves or containers are both cylindrical, they may also have a square, elliptical, octagonal, hexagonal or other polygonal cross section.

2

Where the cosmetic is compressible and the pusher plate will force it upwardly against the converging walls with a change in cross sectional area the walls of both the inner and outer sleeves may also be caused to taper 5 and converge slightly toward the consumption end of the containers.

With the foregoing and other objects in view the invention consists of the novel construction, combination and arrangement of parts as hereinafter more specifically 10 described, and illustrated in the accompanying drawings, wherein is shown an embodiment of the invention, but it is to be understood that changes, variations and modifications can be resorted to which fall within the scope of the claims hereunto appended.

15 In the drawings wherein like reference characters denote corresponding parts throughout the several views:

Fig. 1 is a separated or exploded view of the container construction showing in side perspective view from top to bottom the screw cap, the liner, the tubular shell or 20 body and the screw base.

Fig. 2 is a side elevational view of the assembled self-feeding cosmetic container.

Fig. 3 is a longitudinal vertical side sectional view taken upon the line 3—3 of Fig. 2 and upon a somewhat 25 large scale as compared to Fig. 2.

Fig. 4 is a transverse horizontal sectional view upon the line 4—4 of Fig. 2.

Fig. 5 is a fragmentary top perspective view showing an alternative form of the invention in which the strap or top holder extension for the cosmetic stick extends only 30 part way across the cosmetic stick and leaves the major portion of the top of the stick exposed for application purposes.

Fig. 6 is a fragmentary view partly in section of an 35 alternative top strap or holder construction in which the top strap is of V cross section so more readily to permit the plastic solid cosmetic stick to be pressed upwardly and more readily used.

Referring to Figs. 1 to 4, there is shown a plastic container having a central, tubular body A, a screw cap B, a removable base C, a plastic tubular liner D and a presser or feeder member E.

The members A, B, C and D may be made of metal or 45 plastic but in the preferred construction it has been found that the body A, the screw cap B and the screw bottom C are desirably molded of urea formaldehyde or melamine formaldehyde resin, while the liner B is made of a relatively flexible thin sheet of vinyl resin polyethylene or cellulose acetate plastic.

50 As indicated, the body A is relatively thick at 10 but is reduced in thickness at its upper end 11 and at its lower end 12 to receive the threads 13 and 14, which are desirably square threads but which may if desired be V-threads.

55 The shoulders 15 and 16 at the ends of the threaded portions 13 and 14 act as stops against the edges 17 and 18 of the cap B and the base C.

The cap B is of cup shape and has a series of extensions or scallops 19 to enable a grip by the fingers and 60 removal of the cap B.

Below the scallops are internally threaded at 20 to engage the threads 20 of the body A. The top of the cap B is flat, as indicated at 21, and the interior side walls 22 are substantially cylindrical to continue the cylindrical interior 23 of the sleeve A.

65 The removable threaded base element C also takes the form of a cap, which is much more shallow than the cap B.

The base cup C has a flat bottom 30 with an interiorly threaded flange portion 31 and with a circular ridge 32 extending upwardly and inwardly from the base 30.

70 The liner D consists of a cylinder 33 with an outstand-

ing flange 34 at its lower end. This flange will be positioned in the channel 35 between the ridge 32 and the socket 29 of the screw base C and it will be clamped against the bottom of the channel 35 by the lower end 36 of the body A.

The liner D is also provided with a square cross-section ridge 38 which projects outwardly from the cylinder 33 of the liner D and is clamped between the shoulder 36 of the cap B, and the upper end 37 of the body A.

The liner D at its upper end is provided with the loop or bracket 39, which will stop the upper movement of the solid cosmetic stick but at the same time permit ready access thereto at the sides, as indicated at 40.

In addition, as the cosmetic stick is being used, it will be turned so that the top 41 of the loop 39 will not prevent consumption or usage of any part of the upper end of the cosmetic stick.

The interior of the container also receives the coil spring 50 with the follower plate 51 forming a combined presser or plunger member E.

The lower coil 53 of the spring will be held inside the annular or circular ridge 32 while the edges of the plate 51 will be spaced inside of the interior walls of the cylinder 33.

In usage the cosmetic stick may be filled in to the container A by removal of the screw base 36.

The spring 50 and the plate 51 may be so attached together that they will be removable as a unit from the bottom of the container or tube A upon unscrewing of the bottom cup C.

When the cosmetic stick is inserted into the interior of the shell or container A, the screw cup C may be replaced, pressing the spring 50 so that it will force the stick upwardly in the direction indicated by the arrow 54. At the same time the construction is such to permit the cosmetic stick to be rotated with substantial side pressure as it is being used.

To use the cosmetic stick, the cap B may be unscrewed and the top and sides of the cosmetic stick will be available for pressure against the lips in case of a lipstick or against the eyes in case of an eyebrow pencil or against various parts of the body in case of a plastic cosmetic perfume stick.

Referring to Fig. 5, the alternative strap construction 80 has a transverse portion 81 which only extends part way across the top of the cosmetic stick and may terminate in a prong 82 projecting downwardly in the central portion of the cosmetic stick M. The portion 81 may be molded integrally with the liner or it may be a separate metal insert.

In this type of holder, most of the peripheral area of the top of the cosmetic stick is available for contact with the skin or lips of the consumer of the cosmetic stick or container.

In the embodiment of Fig. 6 is shown another alternative construction in which the transverse portion of the strap 90 is of V-shape or blade shape cross section extending downwardly. This will permit the solid cosmetic stick to press up past the strap 90 as the cosmetic stick is consumed under the pressure of the follower plate E.

As shown where the liner D is of a flexible plastic such as vinyl resin, it will act as a gasket and protect the outer container or shell A from the alcohol or other organic materials in the cosmetic stick.

The liner D may be opaque or transparent and it may be of various colors and it may carry advertising, trademarks or decorative effects, particularly where the shell A is transparent or translucent.

The ridges 34 and 38 which are shown as clamped in position in Fig. 3 may be snapped in position if desired, in which case the upper and lower caps B and C may be telescoped into position without a screw connection.

If desired, in some instances the inner sleeve D and the outer shell A may be molded in one piece as, for example, from a urea formaldehyde resin.

The holder loop or extensions 41, 81 and 90 may be molded or formed integrally with the liner D or they may consist of inserted wires or other elements.

If desired, the liner D and the shell A may converge or be conical upwardly, particularly where the cosmetic stick is sufficiently plastic that its move upwardly under the action of the pressure plate E will be balanced by the compression of the stick. In such case, the plasticity of the cosmetic must be regulated so that it is adjusted to the particular temperature and climate and so that it will not change because of drying out.

Where the temperature changes and the plasticity of the cosmetic vary with drying out of alcohol or other volatile solvents, the sides of the liner D and shell A should be straight.

If desired instead of the ridges 34 and 38 as shown in connection with the liner D, annular narrow gaskets may be employed in the recesses in the cap B and the base C.

The dimensions may be widely varied but it has been found satisfactory in one embodiment of the invention to make the stick of $1\frac{1}{2}$ inch diameter. The liner D may then have an interior diameter of $\frac{3}{4}$ inch and a thickness of about .12 inch.

The entire shell or casing may have a height of $2\frac{1}{2}$ inches with the cap having a height of about $5\frac{1}{4}$ inch and the screw base having a height of $\frac{1}{4}$ inch.

The shell or body A may have a length of 1.929 inches. It is apparent that the applicant has provided a simple, readily manufactured, durable inexpensive self-feeding cosmetic container.

While there has been herein described a preferred form of the invention, it should be understood that the same may be altered in details and in relative arrangement of parts within the scope of the appended claims.

Having now particularly described and ascertained the nature of the invention, and in what manner the same is to be performed, what is claimed is:

1. A self-feeding solid plastic cosmetic stick container having an elongated casing with a follower piston member and a radial obstruction at the upper end thereof consisting of a radially extending flat bar, said bar being provided with wedge-shaped triangular fin means which will engage and project into the solid plastic body.

2. The container of claim 1, in which the bar has a downwardly extending prong adjacent the axis of the casing.

3. The container of claim 1, in which the bar extends only from one side of the container and terminates adjacent the axis of the container and has a downwardly extending prong.

4. A cylindrical solid plastic cosmetic stick dispenser comprising a tubular plastic casing having threaded end connections, a piston in the lower part of said casing, means to propel said piston upwardly to advance said stick from the lower end of the casing to the upper end of the casing and radially inward extensions from adjacent the upper interior end of the casing to engage and retard upward movement of the stick, said extensions being provided with downwardly extending triangular wedge means to project into the upper end of the cosmetic stick, an extra tubular insert being positioned within said plastic casing and said extensions being carried upon said extra tubular insert.
